UNITED STATES PATENT OFFICE.

JACOB SCHWARZ, OF NEW YORK, N. Y.

EASEL.

SPECIFICATION forming part of Letters Patent No. 621,856, dated March 28, 1899.

Application filed January 14, 1899. Serial No. 702,128. (No model.)

To all whom it may concern:

Be it known that I, JACOB SCHWARZ, a citizen of the United States, residing in the city, county, and State of New York, have invented 5 certain new and useful Improvements in Easels, of which the following is a full, clear, and exact description.

My invention relates to easels; and the object of said invention is to provide a simple 10 and efficient support for the picture or other article to be supported upon the easel, which supporting means may be readily attached to an easel of any suitable type or character.

To these ends my invention consists in the 15 novel arrangement and combination of parts hereinafter described and claimed.

In the accompanying drawings, Figure 1 represents a perspective view of an easel embodying my invention. Fig. 2 is an enlarged 20 detail vertical sectional view on the line 2 2 of Fig. 3. Fig. 3 is a transverse sectional view of the same on the line 3 3 of Fig. 2.

In Fig. 1 of the drawings an easel is illustrated which may be of any desired or preferred construction, and said easel is provided 25 with the usual supporting-standards *a*. To each of these supporting-standards is secured a rack-bar *b*, which is detachably secured in place by means of screws *c* or some such 30 equivalent means. Each of these rack-bars is provided at the sides thereof with grooves *d*, which preferably extend throughout the length thereof. Coöoperating with each of these rack-bars is a slide *A*, which, as indicated 35 in Fig. 3 of the drawings, is provided on each side with a longitudinal flange *e*, which is adapted to engage in a groove *d* in the coöoperating rack-bar, and each of these slides may be slid upon its respective rack- 40 bar, as will be apparent from an inspection of Figs. 1 and 3 of the drawings.

The picture-supports *B* are each pivoted near the upper portion thereof to one of the slides *A*, as indicated at *f*, and the lower 45 pending portion of each of these supports *B* is provided with a pawl *g*, which is formed integral therewith and is adapted to engage with its respective rack-bar, as clearly indi-

cated in Fig. 2 of the drawings. At the lower end of each rack-bar is provided a pin *h*, which 50 limits the downward movement of each of the supports and its carrier. By this means the slides *A*, with the supports, may be adjusted as to height when the supports are free from pressure, and when a pressure is exerted upon 55 the supports *B*, as when a picture is supported thereon, they will be secured against movement by forcing the pawls *g* into engagement with the rack-bars *b*, and the greater the pressure exerted upon the supports the more 60 securely will they be maintained against movement.

Having described my invention, what I claim, and desire to secure by Letters Patent, is—

1. An easel comprising suitable supporting-standards, a rack-bar detachably secured to each of said standards, each of said rack-bars being provided with longitudinal grooves therein, a slide adapted to engage in the 70 grooves of each of said rack-bars, a support pivoted at its upper portion to each of said slides and provided with a pawl at the lower portion thereof which is adapted to engage with its respective rack-bar, substantially as 75 and for the purposes specified.

2. An easel comprising suitable supporting-standards, a rack-bar detachably secured to each of said standards, each of said rack-bars being provided with longitudinal grooves in 80 the sides thereof, a slide having engaging flanges adapted to slide in the grooves of each of said rack-bars, a support pivoted at its upper portion to each of said slides and provided with an integral pawl at the lower portion 85 thereof which is adapted to engage with its respective rack-bar, whereby the supports may be adjusted to different heights when they are free from pressure and a pressure exerted upon said supports will maintain the 90 pawls thereon in engagement with the rack-bars.

JACOB SCHWARZ.
